UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,097, dated September 22, 1896.

Application filed August 5, 1896. Serial No. 601,832. Term of patent 3½ years.

To all whom it may concern:

Be it known that I, CHARLES BOOZ, a citizen of the United States, residing at Buffalo, in the county of Erie and State of New York, 5 have invented and produced a new and original Design for Wall-Paper, of which the following is a specification, reference being had to the accompanying drawing, showing a part thereof.

10 The design consists of a series of ornaments formed of interlacing scrolls and connected by vertical stripes formed of interlacing scrolls, as represented in the accompanying drawing.

15 The border for said design also consists of a series of ornaments formed of ornamental interlacing scrolls with a horizontal stripe at the base of said ornaments and formed of interlacing scrolls, as shown in the drawing.

What I claim is—

1. The design for wall-paper herein shown and described.
2. In the design for wall-paper the border herein shown and described.

Witness my hand this 1st day of August, 25 1896.

CHARLES BOOZ.
